UNITED STATES PATENT OFFICE.

JOHN G. AVERY, OF SPENCER, MASSACHUSETTS.

EXPANSION-PULLEY.

SPECIFICATION forming part of Letters Patent No. 443,561, dated December 30, 1890.

Application filed April 23, 1890. Serial No. 349,152. (No model.)

To all whom it may concern:

Be it known that I, JOHN G. AVERY, a citizen of the United States, and a resident of Spencer, in the State of Massachusetts, have 5 invented a new and useful Improvement in Expansion-Pulleys, of which the following is a specification.

This invention relates to the construction of expansion-pulleys and their accessories; 10 and it consists in certain novel combinations of parts hereinafter set forth and claimed. Its objects are, first, to give such pulleys a wide and practically unlimited scope of relative adjustment or change, so as to readily provide 15 for increasing or decreasing the speed of the driven shaft relatively to that of the driving-shaft to any required extent; secondly, to provide for simultaneously opening one pulley and closing the other, so as to 20 gradually change the speed by a simple mechanical device, and, thirdly, to effect such gradual change of speed "automatically," with provision for readily varying the rate of 25 change relatively to the speed of the driving-shaft at will.

In connection with the provision last named and with suitable worm-gearing the improved expansion-pulleys are adapted to take the place of the lever-motion devices commonly 30 employed in connection with pawl-and-ratchet converting mechanism in loom let-offs; but with or without such accessories the improved expansion-pulleys may be employed as machine elements in any kind of machinery 35 where they can be utilized.

Two sheets of drawings accompany this specification as part thereof.

Figures 1 and 2 of the drawings are diagrammatic elevations of a pair of the improved pulleys with their accessories as embodied in a loom let-off, partly in section, showing the parts at or near the respective extremes of their movements. Fig. 3 is an elevation of a pulley detached and partly open; 45 and Fig. 4 is a section on the line 4-4, Fig. 3.

Like letters of reference indicate corresponding parts in the several figures.

Each of the improved expansion-pulleys is constructed in the manner represented by 50 Figs. 3 and 4, to which reference may first be had—that is to say, each pulley is composed of a hub h , adapted to be made fast upon a

rotary shaft by a radial screw s or the like; a hub h^2 , adapted to slide on the same shaft and for heavy work splined thereto, as dotted 55 at s^2 , Fig. 2, and provided with a peripheral fork-groove g or the like; eight (or more or less) belt-carriages c , equally distributed in a central zone; two pairs of uniform lever-arms a b a^2 b^2 in parallel pairs connecting 60 each belt-carrier with both hubs, and suitable pivotal connections at the respective ends of each pair of lever-arms. To form such connections in a suitable way at the belt-carrier ends of the lever-arms, each belt-carrier c , 65 being preferably of malleable iron or steel, is cast with a central web w , Figs. 3 and 4, which projects radially inward, and with end projections or lugs x in the same plane, which extend radially outward, all of which are 70 drilled to receive parallel bolts or rivets r , by which the adjoining ends of the lever-arms are pivoted thereto. To form such pivotal connections at the hub ends of the lever-arms the inner end of each hub is made with flat 75 peripheral surfaces in line longitudinally with the respective belt-carriers, and suitable hinge-pieces or pivotal connections p , Figs. 3 and 4, are attached to said peripheral surfaces and constructed with lugs y z in line 80 longitudinally with said webs w and lugs x , and likewise drilled to receive parallel bolts or rivets r r^2 , by which the corresponding ends of the lever-arms are pivoted therethrough to the hubs h and h^2 , respectively. Cast-iron 85 hubs may thus be readily provided with suitable pivotal connections of malleable iron or steel or other more suitable metal. A pair of such expansion-pulleys P P^2 , Figs. 1 and 2, are mounted, respectively, on a driving-shaft S 90 and a driven shaft S^2 parallel therewith. The two pulleys are reversed end for end relatively to each other, and, having been arranged on the shafts with the belt-carriers of one in line with those of the other and with allowance 95 for the movement of the sliding hubs in opposite directions the required distance, the fast hubs h are tightened on the respective shafts and a suitable driving-belt B is stretched around the two pulleys on their 100 belt-carriers c . The sliding hubs h^2 may then be permanently engaged with the adjusting devices.

To provide for simultaneously opening and

closing the respective pulleys their sliding hubs h^3 are engaged by a pair of forks f at the respective ends of a rigid coupling-bar C , and this is conveniently moved back and forth by means of a sliding bar S' parallel with the shafts S S^2 , which works in fixed guides G and is rigidly jointed to said coupling-bar, as at j .

In the arrangement represented by Figs. 1 and 2 I further provide for automatically adjusting the pair of pulleys so as to gradually increase or decrease the speed of the driven shaft S^2 , and consequently that of rotary motion transmitted therefrom or controlled thereby, with provision for gradually and uniformly increasing or decreasing the rate of change, as aforesaid, and with provision also for readjusting the pulleys by hand. To effect these objects motion is transmitted from said driven shaft S^2 through a worm W , fast thereon, a worm-gear W^2 , and a clutch C^2 to a shaft S^3 , which in turn, through a worm W^3 , fast thereon, and a worm-gear W^4 , fast on a spindle S^4 , drives or controls the rotation of the latter, and said spindle S^4 , through a worm W^5 , fast thereon, and a worm-gear W^6 in mesh therewith, drives a micrometer-screw S^5 . This screw reciprocates a traveling nut N , which is connected with said slide S' by a slotted lever L , engaging with studs on the nut and slide and having a movable fulcrum f' . A movable arm A , to carry the fulcrum f' , has a fixed pivot p' at its opposite end and a slotted sector s' , through which a fastening-bolt b' passes into the fixed frame-part F , to which the arm is pivoted. The "driving-shaft" S receives its motion through bevel-gearing G^0 , or it may be more directly from the power-shaft S^0 , and through the automatic adjusting devices above described a portion of the transmitted power is utilized to slowly and steadily open and close the respective expansion-pulleys so as to change the speed according to a predetermined rule with mechanical accuracy. Said shaft S^2 is further provided with a hand-wheel H , so that when it is unclutched from said worm-wheel W^3 thereon the shaft may be turned by hand so as, through said worm W^3 and worm-gear W^4 , to turn the spindle S^4 either way, and through said spindle S^4 , worm W^5 , worm-gear W^6 , screw S^5 , nut N , lever L , slide S' , and coupling-bar C to readjust the pulleys P P^2 by hand. To increase the scope or capacity for change of expansion-pulleys fitted to given shafts to any required extent, it is only necessary to make the pulleys with lever-arms of greater length. For greater strength the lever-arms at each point may be doubled or applied on both sides of the respective pivotal lugs. In a loom let-off said power-shaft S^0 would be the main shaft of the loom, and said spindle S^4 the warp-beam spindle. The expansion-pulley P would be closed and the expansion-pulley P^2 open, as in Fig. 1, at the beginning of the operation with the warp-beam full, their peripheral speed

being then as one to three. When the warp-beam is nearly empty, the parts appear as in Fig. 2, with the peripheral speed of the respective pulleys reversed or as three to one, and by shifting the fulcrum-arm A the rate of change is increased or diminished in reverse ratio to the distance between the movable fulcrum f' and the pivotal stud on the nut N , so that the warp shall be let off according to the desired number of picks to the inch.

Another intended application of the improved expansion-pulleys is to electric motors for vehicles, so as to provide for driving the axles slow, for maximum power, in starting and in climbing grades, and for gradually increasing the rate of speed of the vehicle at will without changing the speed or power of the motor and without the employment of trains of spur-gearing.

Other applications thereof and additional modifications will suggest themselves to those skilled in the art.

Mechanical details which have not been specified may be of any approved description.

Having thus described said improvement, I claim as my invention and desire to patent under this specification—

1. An expansion-pulley having lever-arms in parallel pairs connecting each belt-carrier with a hub adapted to be fastened on the shaft at one end of the pulley and with a hub adapted to slide on the shaft at the other end of the pulley, substantially as hereinbefore specified.

2. A pair of expansion-pulleys, each having a pair of hubs adapted, respectively, to be fastened on its shaft and to slide thereon, a sufficient number of belt-carriers equally distributed in a central zone, and lever-arms in parallel pairs connecting each belt-carrier with the respective hubs, the sliding hubs being at the opposite ends of the respective pulleys, in combination with a rigid coupling-bar connecting said sliding hubs, a slide parallel with the respective shafts and rigidly jointed to said bar, a belt connecting the pulleys, and a driving-shaft and a driven shaft on which the respective pulleys are mounted, substantially as hereinbefore specified.

3. The combination of a driving-shaft and a driven shaft parallel with each other, a pair of expansion-pulleys mounted on said shafts and each having a fast hub and a sliding hub, a belt connecting said pulleys, a coupling-bar connecting their sliding hubs, a traveling screw-nut connected with said bar, a rotary screw to actuate said nut, and mechanism transmitting motion from said driven shaft to said screw, substantially as hereinbefore specified.

4. The combination, with the pair of expansion-pulleys, their belt, and their shafts, of the shaft S^0 , spindle S^4 , and rotary screw S^5 , worm-gearing connecting the same with the driven shaft and with each other, the traveling nut N , slotted lever L , movable fulcrum-arm A ,

slide S', and coupling-bar C, substantially as hereinbefore specified.

5. The combination, substantially as hereinbefore specified, of the hand-wheel H, shaft S³, spindle S⁴, rotary screw S⁵, worm-gearing connecting said shaft, spindle, and screw, the traveling nut N, lever L, slide S', and con-

necting-bar C, for simultaneously readjusting the expansion-pulleys by hand.

JOHN G. AVERY.
